[57] CLAIM

The ornamental design for a guard for stove heating elements, as shown and described.

DESCRIPTION

FIG. 1 is a rear perspective view of a guard for stove heating elements showing my new design;
FIG. 2 is an enlarged front elevational view thereof;
FIG. 3 is an enlarged rear elevational view thereof;
FIG. 4 is an enlarged side elevational view thereof, the opposite side being a mirror image; and,
FIG. 5 is an enlarged top plan view thereof, the bottom view being a mirror image.

FIG. 1.

FIG. 2.

FIG. 3.

FIG. 4.
